DUST JACKET FOR BOOKS OR THE LIKE

Elva A. Endres, New York, N. Y.

Application July 16, 1952, Serial No. 299,683

2 Claims. (Cl. 281—20)

This invention relates generally to protective coverings and more particularly to a novel dust jacket for the protection of books or similar articles.

The depreciation in the value of books which are infrequently in demand and/or use and which have a relatively long shelf life creates a serious problem that is recognized by publishers, book sellers, librarians, private owners, and others. This depreciation is attributable not only to soil incurred through the handling of books but also is caused by dust and dirt settling and accumulating on the edges of the book leaves which serve as natural depositories therefor. The time and expense involved in the periodic cleaning of such books generally is excessive. Also, in certain instances, for example, where books are edged in gold, cleaning is inadequate and the diminution in book value is substantial.

Heretofore various arrangements have been proposed for the general protection of books and similar articles. Some coverings have been devised primarily to protect books from excessive handling. Such coverings usually protect only the binding of the books, the leaf edges remaining exposed to dust, dirt, and grime. Other devices have taken the form of rigid box-like structures having one open end through which one or more books may be inserted. Such structures, however, are bulky, are designed to enclose only books having certain specified dimensions, and the per unit cost of fabrication thereof is relatively high.

According to the instant invention, an improved protective covering is provided which affords substantially complete protection for the leaves of the book contained therein. The covering is relatively simple in structure, inexpensive to manufacture, and is not limited to the protection of a book of specified dimensions.

An object of the present invention is to provide an improved covering for the protection of books or similar articles.

Another object of the invention is to provide an improved dust jacket for protecting the edges of the leaves of books from dust and dirt.

Another object of the invention is to provide a dust jacket for the protection of the edges of the leaves of books which jacket is adapted for protecting books of different sizes.

A further object of the invention is to provide an improved dust jacket for the protection of books which jacket is relatively simple and inexpensive to manufacture.

A still further object of the invention is to provide an improved dust jacket for books which is serviceable and easy to use.

Other objects and advantages of the invention will be apparent from the following detailed description of various embodiments thereof taken in connection with the accompanying drawings in which:

Figure 1 is a perspective view of the basic form of a dust jacket for books, according to the invention;

Figure 2 is a perspective view illustrating the dust jacket

2

of Figure 1 operably arranged for protecting a book from dust and dirt;

Figure 3 is a plan view of a modification of the dust jacket of Figure 1 including a novel flap closure arrangement;

Figure 4 is a perspective view of the dust jacket of Figure 3;

Figure 5 is a view similar to the arrangement shown in Figure 3 and illustrating a further modification of the invention;

Figure 6 is a fragmentary perspective view of the modification shown in Figure 5; and

Figures 7 and 8 are views of flap closure devices adapted for use with the dust jacket of the invention.

Similar reference characters are applied to similar elements throughout the drawings.

Referring to Figure 1, the basic form taken by the dust jacket of the instant invention comprises a flexible blank 11 of a material such as kraft paper, a treated fabric, or a plastic material having a rectangular central body portion 13 of dimensions substantially equal to the cover dimensions of the book to be protected. Bounding and projecting outwardly from the central portion 13 are flaps 15, 17, and 19 disposed in relation thereto such that the blank 11 is T-shaped in configuration.

A book 21 may be enclosed and protected in the following manner. One cover 22 of the book binding is placed on the central portion 13 of the blank 11 with the title edge of the book oppositely situated with respect to the flap 19. The flap 19 is folded over the exposed leaf edges adjacent thereto and placed in contact with the remaining cover binding 24. Side flap 15 is then folded over the leaf edges 25 and over the folded flap 19 and the remaining side flap 17 is folded over the leaf edges 27 and over the folded flaps 19 and 15. At the point at which flaps 15 and 17 overlap, the dust jacket may be secured about the book, as shown in Figure 2, by some convenient means such as a removable adhesive member 29.

It will be seen that all of the normally exposed leaf edges 23, 25, and 27 of the book thus enclosed are adequately protected from dust and dirt. Also, it is pointed out that, for a set of given book cover dimensions, the dust jacket described above is adapted for enclosing books of materially different thicknesses. By way of example, for books having relatively few pages, the dimension A of flap 19 is selected such that when the flap 19 is folded, the edge 31 falls along the title edge of the book. The dimensions B and C of flaps 15 and 17, respectively, are chosen to provide almost complete overlap thereof. Hence when a relatively thicker book having substantially the same cover dimensions is to be protected, a standard size blank may be used. The overlap, in this case is less than the overlap resulting from enclosing a book having fewer pages. However, the overlap still is sufficient for the overall protection of the book.

Referring to Figure 3, a modification of the basic form of the invention is shown. In Figure 3 a rectangular central portion 13 is indicated generally by dash lines, the portion 13 corresponding in size and in shape to the cover dimensions of a standard size book. Also shown are flaps 15, 17', and 19 projecting outwardly from and bounding the portion 13. Preferably affixed to the flap 15, and located near one end thereof, is a re-inforcing member 37 which may comprise, for example, paper or a suitable fabric or plastic. The re-inforcing member 37 and the flap 15 to which it is bonded include mutually aligned parallel spaced slots 33 and 35. Tab 17' comprises a substantially rectangular cover portion adjacent the rectangular portion 13 which cover portion is graduated into an elongated tongue member 39 having a slot 40. The graduated tongue member 39 preferably is strength-

ened mechanically by a re-inforcing member 41 bonded thereto which is similar in size and in shape to the member 39. The re-inforcing member 41 is slotted at a point corresponding to the slot 40 and preferably is of the same type material as the member 37.

The enclosing of a book may be accomplished in a manner similar to that described hereinbefore with reference to Figures 1 and 2. The book is placed on the rectangular portion 13 with the title edge disposed away from the flap 19. Flap 19 is folded over the book and flap 15 folded over flap 19. Then flap 17' is folded over flap 15 and the tongue member 39 successively threaded through slots 33 and 35. The free end of the tongue member is then folded back upon itself and tucked into slot 40. The book thus enclosed appears as shown in Figure 4.

A modification of the foregoing embodiment of the invention described with reference to Figures 3 and 4 is shown in Figures 5 and 6. Referring to Figure 5, adjacent flap 19, flaps 15 and 17' each includes as integral parts thereof projections 43 and 45 which, when flaps 15, 17' and 19 are in folded position, may be inserted in slots 47 and 49, respectively, of flaps 19. Referring to Figure 6, it may be seen that this feature of the invention affords books and similar articles increased protection from dirt since a more efficient dust-tight closure is provided.

In Figures 7 and 8 there are shown adjustable closing arrangements especially suitable for joining together flaps similar to flaps 15 and 17 of the devices of Figures 1 and 2.

Referring to Figure 7, flap 51 comprises a cover member one end of which is fashioned into a T. The projections 53 and 55 comprising the cross members of the T are adapted to be inserted into one of a number of pairs of slots 57 located in the remaining cover flap 59. It will be seen that the particular pair of slots selected for closing the dust jacket is a function of the number of pages and of the overall thickness of the book thus covered.

In Figure 8, one cover flap 61 of the device includes an arrow shaped projection 63 designed to be contained between any adjacent pair of a plurality of parallel, and preferably equi-spaced, slots 65 located in a second cover flap 67 which is to be secured to the first flap 61. The width of the flat portion 69 of the projection 63, opposite the "arrow point," is selected to be slightly greater than the width of the slots 65. Thus, when the projection 63 is in place between a pair of slots, it is improbable that an accidental or undesired opening of the covering may occur.

In summation, the device herein disclosed and claimed affords a number of advantages not present in the prior art. The dust jacket of the instant invention is relatively simple in structure, inexpensive to manufacture, provides substantially complete protection for all the exposed edges of the book leaves, permits the title edge of the book to remain uncovered for rapid identification, and may be manufactured in standard sizes not limited to the protection of a specific size book.

While the invention has been described as fabricated from certain materials (i. e., paper, fabric, and plastics)

it is clear that the invention is not so limited and may be formed from substantially any suitable flexible material.

What is claimed is:

1. A dust jacket for books comprising a rectangular-shaped flexible body portion, a similarly-shaped flap integral with the body portion and extending from one end thereof and forming a prolongation thereof for folding over and protecting the rear edges of the leaves of a book placed on said body portion, a second similarly-shaped flap integral with the body portion and extending from one side thereof for folding over and protecting a group of leaf edges adjacent the rear edges of the leaves of the book, a third similarly-shaped flap integral with the body portion and extending from the opposite side thereof for folding over and protecting a group of leaf edges opposite the edges protected by said second flap, the end edges of the second and third side flaps being in alignment with the edge of the other end of the body portion, an extension on said third flap forming a prolongation thereof, said extension having tapering end edges continuing into an elongated narrow tongue member, said second flap having a pair of equi-spaced slots parallel to each other and to the free end edge of said second flap for selectively receiving the tongue member, said extension having a slot parallel to the slots in the second flap and being disposed in alignment with the tongue member for receiving the tongue member after passing through a selected slot in the second flap.

2. A dust jacket for books comprising a rectangular shaped flexible body portion, a similarly-shaped flap integral with the body portion and extending from one end thereof and forming a prolongation thereof for folding over and protecting the rear edges of the leaves of a book placed on said body portion, a second similarly-shaped flap integral with the body portion and extending from one side thereof for folding over and protecting a group of leaf edges adjacent the rear edges of the leaves of the book, a third similarly-shaped flap integral with the body portion and extending from the opposite side thereof for folding over and protecting a group of leaf edges opposite the edges protected by said second flap, the end edges of the second and third side flaps being in alignment with the edge of the other end of the body portion, an extension on said third flap forming a prolongation thereof, said extension having tapering end edges continuing into an elongated narrow tongue member, said second flap having a pair of equi-spaced slots parallel to each other and to the free end edge of said second flap for selectively receiving the tongue member, said extension having a slot parallel to the slots in the second flap and being disposed in alignment with the tongue member for receiving the tongue member after passing through a selected slot in the second flap, said second flap being reinforced around the slots formed therein, said extension with its tongue member being reinforced on one face thereof.
